UNITED STATES PATENT OFFICE.

SARA L. RICHARDS, OF NEW YORK, N. Y.

SAFETY EQUIPMENT FOR ELEVATOR-SHAFTS.

1,071,579.

Specification of Letters Patent. Patented Aug. 26, 1913.

Application filed May 5, 1913. Serial No. 765,411.

To all whom it may concern:

Be it known that I, SARA L. RICHARDS, a citizen of the United States, and resident of New York, in the county of New York and State of New York, have invented certain new and useful Improvements in Safety Equipment for Elevator-Shafts, of which the following is a specification.

My present invention relates to a safety equipment for passenger elevator installations.

The object of my invention is to prevent serious accidents to people who inadvertently pass through an elevator door carelessly left open by elevator operators after the car has passed the door. I aim to provide an arrangement that is easily applicable to practically all old as well as new passenger elevator systems, and to avoid complicated mechanisms that might fail to work at the time when most needed.

Figure 1 is a vertical elevation, partly in section, of the passenger elevator shaft equipment. Fig. 2 is a cross section of the shaft at the lower portion, showing the plan of the life saving net.

Like numerals refer to like parts.

The organization comprises the shaft 1, a car 2 for traveling up and down the shaft 1, chains 3 suspended from the car 2, spiral springs 4 suspended from the chains 3, a life saving net 6 held horizontally near the bottom of the shaft 1, and far enough below the elevator for a man in the net not to be crushed by the elevator when it descends to its lowest position, pegs 7 extending from the side walls of the shaft 1, and springs 8 connecting said pegs 7 to said net 6.

The operator runs the car up and down, and leaves the door open inadvertently, as often happens after the car has passed above the door, and if a person should walk through the open door, as often happens, such person will land comparatively safely upon either the life saving net 5 or 6, according to how high up the net 5 happens to be.

My invention reduces to a minimum the loss of life and limb to people using elevators.

My invention may be modified without departing from the spirit thereof. For example, another life saving net may be supported above the car 2 on posts 11 extending upward therefrom. The life saving net 10 is stretched from post to post. The use of this net is obvious; for if the car 2 is below an open door through which a person falls, the net 10 would prevent his falling upon the hard and dangerous top of the car 2.

To prevent the car from falling upon any victim who has fallen into the net 6, I provide a stop in the form of the inwardly sloping walls 13 at such a distance above the net 6 that the car cannot touch a man in the net. Below the net 6 may be laid a mat 12 as a precaution against the rupture of the net when a heavy body falls upon it.

My invention includes making the various parts of any material desired. The nets 5, 6 and 10 may be made of woven wire or rope. The pad 12 may be made of a hair cushion or of a rubber bag filled with air.

I claim as my invention:—

1. The combination of an elevator shaft, a life saving net at the lower end of the shaft, and a stop in the shaft at a height higher than the thickness of a person's body above said net whereby the elevator car in the shaft will be arrested by said stop and prevented from crushing a person lying in said net.

2. The combination of an elevator shaft, a well at the bottom of said shaft and smaller than said shaft in cross-section, a life saving net in said well, and a safety pad below said net.

Signed at New York city in the county of New York and State of New York this first day of May A. D. 1913.

SARA L. RICHARDS.
